TIME CONTROLLED MECHANISM

Filed Sept. 17, 1929 2 Sheets-Sheet 2

UNITED STATES PATENT OFFICE

JOSEPH STELLATO, OF CHICAGO, ILLINOIS

TIME-CONTROLLED MECHANISM

Application filed September 17, 1929. Serial No. 393,203.

This invention appertains to new and useful improvements in time controlled mechanism, and more particularly to a mechanism for operating electrical switches at a predetermined time.

The principal object of this invention is to provide a time controlled mechanism for electrical circuits whereby the circuit may be opened or closed without manual manipulation.

Another important object of the invention is to provide a clock controlled mechanism for actuating a switch or switches of an electric lighting circuit.

These and numerous other important objects and advantages of the invention will become more apparent to the reader after considering the invention as described and claimed hereinafter.

In the drawings:

Figure 1 represents a top plan view of the novel apparatus with the cover plate removed.

Figure 2 represents a vertical sectional view through the housing of the novel device.

Figure 3 represents a cross sectional view of the apparatus.

Figure 4 represents an enlarged fragmentary sectional view.

Figure 5 is a fragmentary perspective view of the rocker arm.

Referring to the drawings wherein like numerals designate like parts, it will be seen that the novel device includes a housing consisting of the bottom 5, end walls 6—6, side walls 7—7 and the closure plate 8 for the open top. This closure plate 8 is provided with an opening 9 therein and is shown in Figure 2.

One side wall 7 of the housing has an opening 10 formed therein and into this projects the face portion of a conventional alarm clock, which in the drawings is denoted by numeral 11. This alarm clock is of the usual construction, the same being provided with the alarm winding key 12.

As is clearly shown in Figure 3, the clock is so situated within the housing that the key 12 will assume a position within the path of one end of the trigger arm 13, when the same is rocked. A post 14 within the hous-

ing pivotally supports the trigger 13 as at 15 and when the trigger is in set position, the trigger has one end resting upon the key 12 of the clock in the manner shown in Figure 3.

A second post, denoted by numeral 16 is suitably secured to one side wall 7 for rockably supporting the arm 17 by means of a pin 18. When the mechanism is in set position, the trigger 13 has its end remote from the clock 11 resting on one end of the rocker arm 17, and in the manner shown in Figures 1 and 3.

The other end of the rocker arm 17, has an offset enlargement 19 and an eyelet 20 protrudes from this end of the arm.

A spring 21 is interposed between the arm 17 and the floor 5 of the housing for urging one end of the arm against the aforementioned trigger 13, and obviously for jerking the opposite end of the said arm downwardly when the opposite end of the arm is released by the trigger 13.

An arcuate slot 22 is provided in one side wall 7 of the housing and through this slot protrudes a projection 23 on the free end of the leaf spring 24. This leaf spring has its free end portion disposed laterally so as to assume a normal spaced position from the inner side of the corresponding side wall so that its projection 23 will only partially project through the aforementioned slot 22.

A winged member 25 serves to secure the opposite end of the leaf spring to the corresponding side wall 7 of the housing.

A flexible element or strand 26 connects at one end to the eyelets 20 and at its opposite end to a switch of a lamp socket, such as the ceiling type. In Figure 1, a wall push-button type of switch is shown in dotted lines and is generally referred to by numeral 27.

It will thus be seen that when the trigger 13 is released by the actuation or unwinding movement of the key 12, the spring 21 will swing the enlarged end of the rocker arm 17 downwardly so that the offset enlargement 19 will ride against the spring 24 so as to shift the laterally disposed free end portion thereof against the corresponding side wall 7, resulting in the engagement of said projection 23 against the wall switch 27, thus

actuating the wall switch to break or close the electric lighting circuit.

Simultaneously a ceiling lamp switch may be actuated by the pull cord 26.

5 While the foregoing description sets forth the invention in specific terms, it is to be understood that various changes may be resorted to when manufacturing this novel mechanism without departing from the spirit 10 of the invention or the scope of the appended claims.

Having described the invention, what is claimed as new is:

1. A time-controlled mechanism for operating switches comprising a rocker arm, 15 a leaf spring, one end of the leaf spring being secured rigidly, the free end portion of the spring being offset across the path of one end of the rocker arm, the opposite end of the said rocker arm being engageable with the winding stem of a clock, said leaf spring being adapted to be moved against a switch when the adjacent end of the rocker arm rides against the same.
2. A time-controlled mechanism for operating switches comprising a rocker arm, a leaf spring, one end of the leaf spring being secured rigidly, the free end portion of the spring being offset across the path of one 20 end of the rocker arm, the opposite end of the said rocker arm being engageable with the winding stem of a clock, said leaf spring being adapted to be moved against a switch when the adjacent end of the rocker arm rides against the same, the free end of the said spring being provided with a projection for engaging the switch to be operated.
3. A time-controlled mechanism for operating switches comprising a rocker arm, 25 a leaf spring, one end of the leaf spring being secured rigidly, the free end portion of the spring being offset across the path of one end of the rocker arm, the opposite end of the said rocker arm being engageable with the winding stem of a clock, said leaf spring being adapted to be moved against a switch when the adjacent end of the rocker arm rides against the same, and a spring, for swinging the said rocker arm when the latter is released by the clock.

In testimony whereof I affix my signature.
JOSEPH STELLATO.
